UNITED STATES PATENT OFFICE.

JOHN HEBERLING, OF ROCHESTER, NEW YORK.

ATTACHMENT FOR LAMP-BURNERS.

1,139,864.

Specification of Letters Patent. Patented May 18, 1915.

Application filed October 5, 1914. Serial No. 865,079.

To all whom it may concern:

Be it known that I, JOHN HEBERLING, of Rochester, in the county of Monroe, and State of New York, have invented a new and useful Improvement in Attachments for Lamp-Burners, which improvement is fully set forth in the following specification and shown in the accompanying drawings.

The present invention relates to attachments for lamp burners, and more particularly to that type which is employed for creating a condition about the wick tube of a lamp burner for the purpose of generating a gas and, in this way, increasing the brilliancy of the burner, an object of the invention being to provide a simple and inexpensive construction which may be readily attached and detached and may be cleaned with ease.

Another object of the invention is to provide a construction in which the maximum gas generating properties are present.

To these and other ends, the invention consists in certain parts and combinations of parts all of which will be hereinafter described, the novel features being pointed out in the appended claims.

In the drawings: Figure 1 is a sectional view through a commercial burner with the present invention applied thereto and shown in section; Fig. 2 is a plan view of the burner with the usual hinged cap removed and the present invention applied thereto; Fig. 3 is an end elevation of the attachment; Fig. 4 is the side elevation; Fig. 5 is an end elevation of another embodiment of the invention; Fig. 6 is a vertical transverse sectional view through the embodiment shown in Fig. 5; and Fig. 7 is a side elevation of the same embodiment.

Referring more particularly to the drawings, 1 indicates a commercial burner of known construction having a hinged cap 2, a wick tube 3, and a perforated diaphragm 4. The attachment is applied to the burner by fitting the same over the wick tube preferably to rest upon the perforated diaphragm. In both forms of the invention, the attachment is an open-ended body having air-intake openings at its lower edge formed by notching the bottom edge at opposite sides as at 5 and at opposite ends as at 6, the portions 7 between the notches serving to rest upon the perforated diaphragm 4. The open-ended body may be held in spaced relation to the wick tube by

any suitable means, lugs 8 in this instance, being bent inwardly from the upper edges of the notches 6 and recessed at their extreme ends to fit the end walls of the wick tube.

The body is preferably oval-shaped in horizontal cross section and from the notches or air inlets 5 and 6, the side walls 9 and end walls 10 extend perpendicular, the end walls each being perpendicular throughout its height while the side walls are provided with air inlets 11 in the form of horizontal slots extending substantially throughout the lengths of the side walls and in a horizontal plane with the upper end of a wick tube to which the attachment is applied. Above these slots, the side walls are bent or deflected at 12 at an angle to the plane of the portions of the side walls below the slot, the opposite edges of each deflected portion lying on opposite sides of the plane of the portion of the side wall below the slot.

In the embodiment of the invention shown in Figs. 5, 6, and 7, a flange or tongue 13 projects inwardly from the lower edge of each slot.

According to this invention, air will pass through the holes of the diaphragm 4 and the notches 5 and 6 into the lower end of the body to be heated by radiation from the wick tube and the open-ended body. Air will also pass through the slots 11 being previously heated by the exterior walls of the open-ended body and trapped by the deflected portion 12 which extends beyond the plane of the walls 9. This trapped air discharges directly onto the upper end of the wick tube where it is most needed, mixing at the same time with the heated air which is ascending in the open-ended body from the bottom of the latter. The delivery of the air in the above manner, together with the intense heat created about the wick, produces a very brilliant light, and this is due to the heating of the liquid fuel to produce a gas and the proper supply of air to the gas thus generated. The tongues 13 of the embodiment shown in Figs. 5, 6, and 7 increase the force of the currents of air delivered through the openings 11, and, at the same time, deflect toward the wick, the ascending currents within the body.

What I claim as my invention and desire to secure by Letters Patent is:

1. An attachment for lamp burners comprising an open-ended body formed with air

inlet notches in its lower edge and with side and end walls extending vertically from the lower edge of the body, the side walls being provided with openings near their upper edges and being deflected inwardly above said openings.

2. An attachment for lamp burners comprising an open-ended body formed with air inlet notches in its lower edge and with side and end walls extending perpendicularly from the lower edge of the body, the side walls being provided with horizontal slots at points opposite the upper end of the wick tube of the burner to which the attachment is to be applied, and said side walls also being bent above said slots so that the upper edge of each bent portion lies on the inner side of the vertical plane of the lower portion of such side wall and the lower edge lies on the outer side of said plane.

3. An attachment for lamp burners comprising an open ended body having horizontal slots in opposite side walls, the portions

of the side walls above each slot being bent at an angle to the plane of the portions of the side walls below such slot.

4. An attachment for lamp burners comprising an open-ended body having horizontal slots in opposite side walls, the portions of the side walls above each slot being bent at an angle to the plane of the portions of the side walls below such slot and projecting on opposite sides of said plane.

5. An attachment for lamp burners comprising an open-ended body having horizontal slots in opposite side walls, a tongue extending inwardly from the lower edge of each slot, and the portions of the side walls above each slot being bent at an angle to the plane of the portions of the side walls below such slot and projecting on opposite sides of said plane.

JOHN HEBERLING.
